UNITED STATES PATENT OFFICE.

CALEB E. SUMMERS, OF DAYTON, OHIO, ASSIGNOR TO GENERAL MOTORS RESEARCH CORPORATION, OF DAYTON, OHIO, A CORPORATION OF DELAWARE.

METHOD OF AND DEVICE FOR TEMPERATURE COMPENSATION.

Application filed January 17, 1923. Serial No. 613,250.

To all whom it may concern:

Be it known that I, CALEB E. SUMMERS, a citizen of the United States of America, residing at Dayton, county of Montgomery, 5 and State of Ohio, have invented certain new and useful Improvements in Methods of and Devices for Temperature Compensation, of which the following is a full, clear, and exact description.

10 This invention relates to improvements in methods of and devices for temperature compensation and in its preferred form relates more specifically to valve operating mechanism for internal combustion engines 15 and means for compensating for changes in adjustment produced therein by changes in temperature.

Among the objects of the invention is to preserve the adjusted relation in operating 20 mechanism which relation normally tends to vary with the variation of temperature.

Another object of the invention, as applied to valve mechanism, is to decrease 25 noise in such mechanism occasioned by change in adjustment which is caused by variation in operating temperature.

Still another object is the elimination of 30 variation in valve clearances and consequent changes in valve timing due to increase or decrease in temperature.

With these and other objects in view the invention comprises means caused to be actuated by changes in temperature which means compensates for the differential expansion of 35 different portions of the mechanism, for example, valve stems and push rods, and maintains the adjustment which has been made previous to temperature change. For example, the means tends to maintain the ad- 40 justed alignment of the top of the push rod, the center of the rocker arm shaft and the top of the valve stem when applied to "over- head valve" mechanism in internal combustion engines.

45 The invention will be more readily understood by referring to the accompanying drawings in which a preferred form of embodiment of the invention has been illustrated and in which:

50 Fig. 1 illustrates a view of an air cooled cylinder to which the invention has been applied.

Fig. 2 is a side view of a pair of such air cooled cylinders, looking at the side upon which the push rods are located.

55 Fig. 3 is a view of the cylinders of Fig. 2 looking at the other side.

Fig. 4 is a view analogous to that of Fig. 1, showing the invention applied to water cooled cylinders.

60 In the operation of the ordinary engine, particularly those having so called "over-head valves", the cylinders become much more highly heated than the push rods, which usually extend parallel with the cylinders outside of the more intense heating influence thereof. In such engines usually the frame work, carrying the rocker arms mounted on suitable shafts, is carried by the cylinder head and accordingly, is in the process of expansion of the cylinder, lifted away from the end of the push rod during the 65 operation of the engine. The result of this difference in expansion of the cylinder and push rod is an increase in the adjusted clearance between the upper end of the push rod and the end of the rocker arm with which it is designed to coat. As a result of such increased clearance there is a difference produced in the valve clearance and a difference 70 in the timing of the valve, these differences being due to the lag in operation of the valve caused by the time consumed in the action of push rod in taking up the excessive clearance between it and the rocker arm. It 75 will readily be seen that such operation tends to decrease the efficiency of the engine and also tends to cause noisy valve operation and the hammering of the valve upon its seat with a consequent injury to both the valve 80 and the seat.

85 In the present form of engine, as the differential expansion takes place in the push rod and cylinder, and as the rocker arm, which is mounted upon the end of the cylinder, tends to move away from the push rod, the fulcrum of the rocker arm, namely the rocker arm shaft, is moved positively in the opposite direction a sufficient distance to 90 compensate for the differential expansion. The adjusted clearance between the upper end of the push rod and the adjacent end of the rocker arm is therefore substantially maintained during operation of the engine.

In the form of embodiment of the invention which is illustrated in the accompanying drawings (Figs. 1, 2 and 3) there is shown an air cooled internal combustion engine cylinder at 10 having mounted upon its head a superstructure assembly, indicated as a whole by the numeral 11, which assembly includes an intake pipe 12 common to two cylinders and an exhaust pipe 13 for each of them. The assembly also carries the valve and valve springs each indicated as a whole by the numeral 14. The assembly also carries the rocker arms 15 for operating the valves, which rocker arms are mounted on a shaft 16 mounted in a frame 17.

This frame 17 is a rigid frame provided with bearings 18 for the shaft 16 and is supported on four posts, of which, in the present instance, two are carried at each end of the superstructure assembly, as shown most clearly in Figs. 2 and 3. Of these four posts, two numbered 20, are preferably integral with the superstructure casting and of the same material. These posts 20 are of substantial size and have their upper ends rounded as shown most clearly in Figs. 1 and 4. The frame 17 is secured to the rounded upper end of post 20 by means of a short screw or bolt 21 extending through a portion of the frame and into a suitable hole in the top of the post.

The other two posts which support the frame 17 are designated by the numeral 25 and these posts are made of a material which has a different coefficient of expansion than posts 20. In the specific form shown in the drawings, the posts 25 are made of aluminum which has a coefficient of expansion something more than twice that of cast iron which is the usual material for engine cylinders and superstructure castings. In the form illustrated the posts 25 consist of short rods of aluminum threaded into suitable bosses on the superstructure casting at their lower ends and provided at their upper ends with reduced threaded portions which extend through suitable portions of frame 17 and are secured therein by nuts 26.

The push rods for operating rocker arms 15 are designated by the numeral 30.

In Fig. 4 the same structure is illustrated as applied to a conventional water cooled engine cylinder. In such cylinders the same difficulties arise with "overhead valve" mechanism and the same solution of the problem can be applied. Like numerals apply to like parts in this view as in the others.

In the operation of the device described above, the proper adjustment between the push rod 30, the rocker arm 15 and the valve 14 is made with the engine cold, and, if the engine is put in operation and the various parts begin to expand from being heated, then post 25, being heated to sub-

stantially the same temperature as the material of the superstructure or head of the cylinder, will expand to a considerably greater degree than do posts 20. The effect of this is to tilt the frame 17 through a small angle upon the rounded tops of posts 20, producing the result that the rocker arm shaft 16 is moved positively toward the base of the cylinder. The consequence of this movement is that the rocker arm 15 is moved downward to compensate for the failure of the push rod 30 to elongate as much as does the cylinder. It is obvious that the line of contact between the tops of posts 20 and the contacting faces of frame 17 must be located at the proper place along the line representing the distance between post 25 and shaft 16, as upon this location will depend the accuracy of the compensation. It is obvious that if this line of contact is closer to post 25 than it should be, the shaft 16 will be moved downward to a greater degree than necessary to compensate for the tendency to change the adjustment, and, if close enough to post 25, may cause the valve to be held permanently open during the heated condition. On the other hand, if this line of contact is too far from the post 25, the movement of shaft 16 will be insufficient to take up the increased clearance due to higher temperatures.

It is also contemplated using a material which has a less coefficient of expansion than the material of the cylinder and push rod and applying it in suitable fashion.

In fact it is within the purview of the invention to compensate for change in adjustment of devices of the character mentioned occasioned by changes in temperature, by positively moving one or more of the elements as distinguished from attempts to compensate by restraining movement of parts which movement is tended to be caused by expansion or contraction with increase or decrease in temperature.

While the form of mechanism herein shown and described, constitutes a preferred form of embodiment of the invention, it is to be understood that other forms might be adopted, all coming within the scope of the claim which follows.

What I claim is as follows:

In combination in an internal combustion engine having a cylinder, a head therefor, a valve for closing a port in the head and opening into the cylinder, and an oscillating valve operating member for moving said valve to open said port; two posts spaced apart from one another and extending upwardly from said head, and which posts are made of the same material as said head; a frame pivotally connected with the upper ends of said posts and supported by said members; a shaft carried by said frame and whereupon said oscillating valve

operating member is supported; and another post carried by said head and extending upwardly therefrom and spaced apart from said first mentioned post, said last mentioned post being made from a material having a greater coefficient of expansion than said first mentioned posts and the

upper end thereof being connected with said frame, whereby said frame is rocked and said shaft is moved toward said head as the cylinder expands due to heating thereof. ¹⁰

In testimony whereof I hereto affix my signature.

CALEB E. SUMMERS.
